UNITED STATES PATENT OFFICE.

ROBERT SOHNER, OF VIENNA, AUSTRIA.

MOTOR PLOW.

Application filed February 27, 1924. Serial No. 695,444.

To all whom it may concern:

Be it known that I, ROBERT SOHNER, subject of the Republic of Austria, residing at Vienna X, Knollgasse 35, Austria, have invented certain new and useful Improvements in Motor Plows, of which the following is a specification.

My present invention relates to motor plows, and has particular reference to 10 mechanism for raising and lowering the share frame.

In motor plows of this general construction, mechanism for raising and lowering the share frame by means of power from the 15 motor has heretofore been provided, but such devices have generally been of elaborate construction, embodying complicated change gears, and as a result much annoyance has been caused by frequent defective operation, and difficulty has been encountered in 20 properly operating and supervising the raising and lowering of the share frame.

An object of the present invention is to provide a mechanism of this character 25 which is of relatively simple construction, and positive in operation.

A feature of the invention lies in providing means for lifting the share by means of power from the motor, and permitting the lowering of the frame to a predetermined furrow depth to be effected by the force of gravity.

Another feature of the invention lies in providing means for locking the frame automatically to hold it in a predetermined raised position, and in providing adjustable means for automatically limiting the fall of the frame to a predetermined amount when the locking means has been disengaged to 40 permit the frame to fall of its own weight.

For the attainment of the foregoing objects, and such other objects as may herein-after appear or be pointed out, I have illustrated one embodiment of my invention in 45 the accompanying drawings, in which—

Fig. 1 is a longitudinal cross-section through the mechanism, the share frame being omitted;

Fig. 2 is a plan view of a portion of a 50 motor plow equipped with my improved device;

Fig. 3 is a cross-sectional view taken along the line III—III of Fig. 1; and

Fig. 4 is a cross-sectional view taken 55 along the line IV—IV of Fig. 2.

Referring now to the drawings, I have

shown a chassis frame 1 of a motor plow, carrying a share frame 2 provided with shares 3 arranged toward the rear of the chassis 1 in a well-known manner. The 60 share frame 2 may be attached toward the front of the chassis by any suitable well-known means.

A lifting gear α is provided to operate directly or indirectly upon the share frame 2, and is arranged to be operatively, yet disengageably, connected with the engine shaft 4 by means of a clutch k . In the illustrated embodiment, I have shown the clutch k as a friction clutch, the driving part 10 65 being provided with peripheral teeth 11 engaging constantly with a worm 12 keyed upon a shaft 13 driven by the engine shaft. The shaft 13 is mounted in bearings 14 provided in a casing 15 which encloses the entire clutch k . The shaft 13 is operatively coupled to the engine shaft 4 by means of a universal joint 17. The driven part 20 of the clutch k is splined by means of keyways 21 upon a transverse shaft 22 leading 70 to the lifting gear α .

When the clutch k is engaged, the lifting gear α is driven directly from the motor by means of the shaft 4, the shaft 13, the clutch k , and the shaft 22. The clutch is provided 85 with a control lever which comprises a bent lever 25 pivoted to the casing 15 at 26, and provided with a forked end portion 25¹ adapted to engage a sliding sleeve 27 carried by the driven part 20 of the clutch. 90 The other arm 25¹¹ of the lever 25 is operatively articulated to a rod 28 leading to a suitable control member such as a pedal arranged within the driver's reach. The spring 29 extends between the arm 25¹¹ and a fixed point on the chassis frame 1 to normally hold the lever 25 in a position disengaging the clutch k ; that is, the rod 28 acts upon the lever 25 against the tension of the spring 29. 95

The lifting gear α comprises a pinion 35 carried by the shaft 22 and engaging a toothed member or rack 36, the latter being slidably mounted in fixed guides 37 and connected by means of a pin 38 (Fig. 4) with 100 the share frame 2.

The automatic locking means for retaining the share frame in a predetermined raised position comprises preferably a shoulder 40 provided on the rack 36, and a pawl 110 41, pivoted as at 42, adapted to cooperate and engage with the shoulder 40. The pawl

41 has two arms, one thereof constituting the pawl proper, and the other thereof being articulated to a rod 43 leading to a suitable control member such as a pedal provided 5 within the driver's reach. A spring 45 similar to the spring 29 is positioned between the pawl and a fixed point on the chassis frame 1 to urge the pawl proper constantly against the rack 36 so that when the shoulder 40 10 assumes a position adjacent to the pawl 41, the latter will be urged and will remain in engagement with the shoulder 40.

Adjustable means are provided for automatically limiting the fall of the share frame 2 to a predetermined amount when the locking device 41 is disengaged, and this automatic control means, indicated generally by the reference numeral *z*, comprises preferably adjustable stop bolts removably insertable at desired points, such as holes 50 provided in the rack 36, and adapted to encounter a fixed point, preferably the upper end of the fixed guide 37, when the share frame 2 and the rack 36 drop by their own weight. 15 Thus, in the illustrated embodiment, I have shown a stop bolt 51 removably inserted into one of the holes 50, and adapted to engage the fixed stop 52 constituted by the upper edge of the guide 37. 20 The lifting gear *w* is also provided with means for automatically disengaging the clutch *k* when the share frame 2 has been lifted to a predetermined raised position. This disengaging means is preferably carried by the toothed member 36, and comprises preferably a portion constituting a cam surface 53 cooperating with the lever 25 which is disposed to lie within the path of movement of the surface 53. More specifically, the lever 25 is guided in a slot 54 in such a manner that it can move sidewise, but not upwards or downwards. Adjacent to the cam surface 53, I provide a locking surface 55 parallel to the direction of movement of the rack 36; and the cam surfaces 53 and 55 are so arranged that when the pawl 41 is in engagement beneath the shoulder 40, the lever 25 will lie in engagement with the locking surface 55. By this means, the lever 25 30 is firmly retained in disengaged position.

The extension shaft 13 carries at its rear end a connecting pin 60 adapted to be coupled with a coupling sleeve 61 of the clutch device *w*. The sleeve 61 is carried by a shaft 62 mounted to slide axially and carrying a clutch 63 constantly acted upon by a spring 64 to keep the device *w* normally uncoupled from the shaft 13. The shaft 62 is provided at its rear end with a crank 65.

60 The device operates as follows:—

The clutch *k* is normally held in disengaged position by the spring 29 which acts upon the lever 25. If it is desired to raise the share frame, the operator actuates the rod 28 against the action of the spring 29 to

engage the clutch *k*. Operative connection will then be established between the motor and the shaft 22, and the pinion 35 will operate to raise the rack 36 carrying with it the share frame 2. As the rack 36 approaches its highest position, the cam surface 53 encounters the lever 25 and engages the latter to move it in the slot 54 in a direction to disengage the clutch *k*. The clutch *k* is not entirely disengaged however until the locking cam surface 55 has reached the point alongside of the lever 25 to retain it in its extreme disengaged position. Simultaneously, the shoulder 40 will have assumed a position immediately above the pawl 41, and the latter, under the action of the spring 45, will snap into place beneath and in engagement with the shoulder 40, thereby retaining and locking the rack 36 (and the share frame *z*) in its highest position. It will be noted that this locking device is entirely independent of the driving mechanism, the entire weight of the share frame being carried by the pawl 41. When it is desired to lower the share frame, the driver of the plow operates the rod 43 against the action of the spring 45 to withdraw the pawl 41 from engagement with the shoulder 40. As a result, the share frame and the rack will fall by their own weight. The amount of their descent will be limited however to a predetermined adjustable amount by virtue of the fact that the bolt 51 will strike the fixed stop 52. The bolt 51 will have been previously inserted into a desired opening 50 depending upon the depth of furrow which is required.

By virtue of this construction and arrangement, the movement of the shares 3 can be positively controlled with great ease and in a manner whereby almost immediate response is secured. Merely operating the rod 28 will serve to raise the shares quickly and expeditiously; and after they have been raised, and retained in raised position, the mere operation of the rod 43 will cause them to drop almost instantaneously to a predetermined depth.

It will be obvious that various details in the construction herein illustrated and described for the purpose of explaining the nature of my invention may be altered and changed by those skilled in the art without departing from the spirit and scope of the invention as expressed in the appended claims. It is therefore intended that these details be interpreted as illustrative and not in a limiting sense.

What I claim is:—

1. In a motor plow, the combination with a share frame, of means including a toothed member and disengageably operatively connected to the motor for lifting said frame, and means carried by said member for automatically disengaging said first named

- means from said motor when the frame has been raised to a predetermined position.
2. In a motor plow, the combination with a share frame, of means including a toothed member carried by the frame and disengagably operatively connected to the motor for lifting said frame, means carried by said member for automatically disengaging said first named means from said motor when the frame has been raised to a predetermined position, and means cooperating with said member for automatically locking said frame in said raised position.
3. In a motor plow, the combination with a share frame, of means including a toothed member carried by the frame and disengagably operatively connected to the motor for lifting said frame, means carried by said member for automatically disengaging said first named means from said motor when the frame has been raised to a predetermined position, means cooperating with said member for automatically locking said frame in said raised position, and adjustable means carried by said member for automatically limiting the fall of the frame to a predetermined amount when the locking means is disengaged to permit the frame to fall of its own weight.
4. In a motor plow, the combination with a share frame, of means for lifting the frame and comprising a toothed rack connected with the frame and a pinion meshing therewith, a clutch for operatively engaging or disengaging said means with the motor, and means carried by said rack and adapted to cooperate with said clutch for automatically disengaging the latter when the frame has been raised to a predetermined position.
5. In a motor plow, the combination with a share frame, of mechanism for raising the frame by the motor, said mechanism comprising a toothed rack connected with the frame, a pinion meshing with the rack, a clutch for establishing operative connection between the pinion and the motor, means carried by the rack for automatically disengaging said clutch when the frame has been raised to a predetermined position, and means cooperating with the rack for automatically locking the frame in said raised position.
6. In a motor plow, the combination with a share frame, of a toothed rack connected therewith, a fixed guide therefor, a pinion meshing with the rack and drivable by the motor to lift the frame, means cooperating with the rack for automatically locking the frame in a predetermined raised position, and adjustable stops carried by the rack and adapted to encounter said fixed guide when the locking means is disengaged to permit the frame to fall by its own weight.
7. In a motor plow, the combination with a share frame, of a toothed rack connected therewith, a fixed guide therefor, a pinion meshing with the rack and drivable by the motor to lift the frame, means cooperating with the rack for automatically locking the frame in a predetermined raised position, said rack having a plurality of openings therein, and a stop bolt removably inserted in one of said openings and adapted to encounter the fixed guide to limit the fall of the frame by its own weight when the locking means is disengaged.
8. In a motor plow, the combination with a share frame, of a toothed rack connected with the frame and having a shoulder, a pinion meshing with the rack, means for driving the pinion by the motor to lift the frame, and means cooperating with the rack for automatically locking the frame in a predetermined raised position, said last named means comprising a pawl automatically movable into engagement with said shoulder.
9. In a motor plow, the combination with a share frame, of a toothed rack connected with the frame, a pinion meshing with the rack, and a clutch including a control lever for establishing operative connection between the pinion and the motor to lift the frame, said rack having a portion constituting a cam surface adapted to encounter and move said lever to disengage the clutch when the frame is in a predetermined position.
10. In a motor plow, the combination of elements as set forth in claim 9, said cam surface being of a shape to retain said clutch in disengaged position while the frame is in said raised position.

In testimony whereof I affix my signature

ING. ROBERT SOHNER.
